UNITED STATES PATENT OFFICE.

CHARLES AVERY KENNEDY, OF COATICOOK, QUEBEC, CANADA.

FURNACE-CASING.

1,089,843.

Specification of Letters Patent. Patented Mar. 10, 1914.

Application filed July 12, 1909. Serial No. 507,234.

To all whom it may concern:

Be it known that I, CHARLES AVERY KENNEDY, of the town of Coaticook, in the Province of Quebec and Dominion of Canada, a 5 subject of the King of Great Britain, have invented certain new and useful Improvements in Furnace-Casings, of which the following is a full, clear, and exact description.

My invention relates to improvements in 10 casings for furnaces and the like, and the object is to provide an inexpensive and efficient casing which will greatly reduce the radiation of heat from the furnace.

A further object is to provide a casing 15 which may be easily taken apart or assembled to clean or repair the furnace proper.

To accomplish these objects, I provide a casing formed of hollow sections which may be readily bolted together. Each section 20 comprises a hollow body having a flange on one or more edges forming a rabbet for the reception of the edge of the next section.

In the drawings which illustrate my invention:—Figure 1 is a vertical sectional view 25 of the device showing the furnace in elevation with part thereof broken away. Fig. 2 is an enlarged sectional view of a portion of the casing showing the method of uniting the sections and inserting the hot air thimbles. 30 Fig. 3 is a partial sectional view showing the cold air inlet.

In the above defined figures, 4 designates a furnace fire-box, and 5 a radiator located thereabove and discharging the products of 35 combustion through a flue 6. The furnace and radiators are surrounded by a casing comprising side, top back and front sections 7, 8, 9 and 10 respectively, the latter of which, 10, may be a single sheet or casting, 40 as is generally used. With the exception of the front, all the sections are built up of an outer wall 11 and an inner wall 12 spaced therefrom. The walls unite in a flange 13 in line with the outer wall. Each wall is 45 lined with sheets 14 of asbestos or other suitable insulating material, held in place by strips or plates 15 of metal riveted through the insulating material, to the wall. Whenever necessary to prevent the walls of the 50 sections from bending or buckling, they are stiffened by channel shaped members 16 which are held in place and against which the walls of the casing are drawn by bolts 17. The sections are united preferably by means 55 of an angle iron 18 shaped as shown in Figs. 1 and 2, which is riveted to the flange of one

section and fits over the flange of the other section to which it is secured by stove bolts 19, or other suitable means. The front section 10 is provided with a peripheral flange 60 20 which lies against the flanges of the surrounding sections and is secured thereto by a U-shaped member 21 and bolts 22. A cold air inlet 23 is provided in the side section of the casing near the bottom. This inlet 65 comprises an outwardly flanged outer sleeve 24 located between the walls of the section and an outwardly flanged inner sleeve 25 which fits snugly within the outer sleeve. The walls and insulation are pressed together between the flanges of the sleeves and the insulation thus held in place. A similar sleeve 26 is located in the top 8, to provide outlet for the smoke flue 6. The hot air outlet pipes 27, which extend through the casing, comprise a flanged outer sleeve 28 located between the walls of the top section, and an inner sleeve 29 flanged at the inner 70 end and fitting tightly inside the outer sleeve. This inner sleeve projects above the casing 75 and the projecting portion thereof is surrounded by a locking sleeve 30 secured thereto by rivets, or bolts 31. The walls of the casing and the insulation are held rigidly in their places between the flanges of the sleeves. 80 If for any reason it is found desirable to make the sections in two or more parts, a union may be effected between said parts by riveting metal straps 32 to the inner and outer walls of one part of the section so that 85 a portion of the straps project above the edge of the part. The other part of the sections is then placed between the edges of the straps 32 and secured by bolts 33 when 90 erecting the casing. 95

In erecting the casing the front section 10 is secured to the furnace and radiator, the side sections 7 being secured thereto by the angle irons 21 and bolts 22, the back sections 9 secured to the side sections by the angle 100 irons 18, and lastly, the top section 8 secured in place between the front, back and side sections by the angle irons 18 and 21. Cold air enters the casing through the orifices 23, is heated by radiated heat from the furnace 105 and radiator and delivered through the hot air thimbles 27.

It will be obvious from the foregoing description, that I have provided an inexpensive furnace casing which may be readily and 110 quickly assembled or taken apart. The sections are all flat and may be easily handled,

shipped or stored, at a minimum cost. The use of a dead air space between the insulated walls forms a non-absorbent casing which will economize the heat generated by the furnace and deliver practically all of said heat through the hot air thimbles to the heating flues.

Having thus described my invention, what I claim is:—

- 10 A furnace casing comprising a plurality of hollow sections, a flange on the edge of each section forming a rabbet, the edge of

one section resting in the rabbet of the adjacent section, the flange of said first section projecting transversely beyond the flange of the second section, and a grooved strip secured to the flange of the second section and embracing the flange of the first section. 15

In witness whereof I have hereunto set my hand in the presence of two witnesses.

CHARLES AVERY KENNEDY.
